UNITED STATES PATENT OFFICE.

VLADIMIR SCHEWELIN, OF MOSCOW, RUSSIA, ASSIGNOR TO LA SOCIÉTÉ ANONYME
WOLOKNO SCHEWELIN, OF MOSCOW, RUSSIA.

TREATMENT OF VEGETABLE FIBERS AND MATERIALS.

1,020,625.

Specification of Letters Patent. Patented Mar. 19, 1912.

No Drawing.

Application filed June 22, 1911. Serial No. 634,759.

To all whom it may concern:

Be it known that I, VLADIMIR SCHEWELIN, a subject of the Emperor of Russia, residing at Moscow, Russia, have invented certain new and useful Improvements in the Treatment of Vegetable Fibers and Materials, of which the following is a specification.

It is well known that warm alcohols have a cleansing and softening effect upon raw fibers such as flax, hemp, and the like and various processes have been devised for utilizing alcohols to prepare the fibers for spinning and weaving.

This invention relates to an improved process for treating flax, hemp, cotton and similar fibers with warmed alcohols, whereby a greatly improved product is obtained the said process being applicable to raw fibers, spun thread, yarn or woven fabric.

Further, hemp fiber, on the Russian market particularly, is mostly coarse and suitable only for the lowest thread numbers, but by chemically treating this fiber by my process, it can be made to produce not only the lower thread numbers but numbers even higher than 40.

Notwithstanding the fact that a preparatory chemical cleansing of the hemp fiber offers great advantages in that finer threads can be spun, it is not at present employed in practice as heretofore no cleansing process applicable both to the treatment of raw fiber and spun thread has been known.

According to the process I propose, the fiber, thread, or woven fabric, is submitted to fewer operations than is usually the case, and becomes lustrous and soft to the touch. When fibers are treated they are not twisted, bent, or stuck together, or reduced to fine or short filaments, which latter is a most important point in weaving. Also, the same method of cleansing, more energetically applied, reduces the fibers to fine filaments, without however, impairing the soundness of the cellular tissue said filaments being easily converted by suitable machinery into a material resembling cotton wool.

According to my invention the raw fiber, spun thread, or woven fabric, is first boiled or steamed in a closed vessel containing an alkaline solution to which has been added a mixture of alcohol, and naphthenic acid. This naphthenic acid occurs naturally in oils

from the Baku district, and is also contained in the organic acid residues obtained in the refining and manufacture of naphtha and the term naphthenic acid in this present specification is intended to cover the use of such acid residues. After a certain time the solution is drawn off and the materials are preferably rinsed with hot water and then treated with a supply of warmed alcohol with or without the addition of naphthenic acid. This alcohol is preferably circulated through the materials by suitable stirrers, or other means, and the vessel is warmed to a suitable temperature. After a time the alcohol is withdrawn and if a greater degree of cleansing or softness is desired a fresh supply of alcohol, with or without the addition of naphthenic acid is run into the vessel and the warming continued. This treatment with alcohol may be repeated several times until the desired degree of cleanliness and softness is reached. The alcohol is then finally withdrawn and the materials dried by means of hot air or superheated steam.

All the above operations may be carried out in one and the same vessel and the used alcohol may be regenerated by distillation in the known manner in a still.

In a suitable method of carrying out my process the materials to be treated are boiled or steamed to a temperature of between 90° and 100° C. in an alkaline solution which may be caustic soda of a density of 1° to 1½° Baumé for materials of flax and hemp, but not of a higher density than ½° Baumé for cotton materials. To this alkaline solution is added 1% of the weight of the materials treated of ethyl alcohol, and ½% of naphthenic acid. The ethyl alcohol used is preferably unpurified and is mixed with fusel oil or with 5% of methyl alcohol, or other alcoholic impurity but alcohols other than ethyl alcohol may equally well be employed. The materials are heated in the above solution to a temperature not exceeding 100° C. at which temperature the alcohol vapor has a tension of two atmospheres, the solution being preferably circulated or agitated by means of stirring for about six hours, after which the solution is run out and the materials rinsed with hot water. A further supply of alcohol is then run into the vessel which is then heated up to between 65°

to 70° C. the strength of the alcohol being greater than 60° according to Tralles alcoholmeter. This alcohol may be a mixture of ethyl alcohol and naphthenic acid in the 5 proportions above described or any other suitable alcohol with or without the addition of fusel oils may be used. After about one hour the alcohol is withdrawn and if a high degree of cleanliness is desired a fresh 10 supply run in, the heating being continued for two hours the alcohol being then finally removed and the contents of the vessel dried by means of steam or hot air. If for the 15 second application of the spirit, alcohol of a strength of 90° to 95° Tralles is used, there is no necessity to dry the materials, thus a great saving of expense is effected. The 20 used alcohol is regenerated by distillation in any known convenient manner.

25 It has been found that the cleansing effect is increased if a small amount of a fatty acid containing 18 carbon atoms such as stearic or oleic acid be added to the solution of alcohol and naphthenic acid, or to the 30 solution of alcohol alone when such is used, for example, an amount of stearic acid equal to $\frac{1}{4}\%$ of the weight of the alcohol used may be usefully added. Also, the effect is further strengthened if $\frac{1}{16}\%$ by weight of light 35 coal oil be added together with the stearic and oleic acids.

In the above manner, raw fibers, spun thread and woven fabric may be treated, said materials being bleached to a perfect 40 whiteness more easily and in fewer operations than usual, and being better able to stand subsequent treatment with a chlorid. Cotton fiber and its products may be treated by my process. Also flax and hemp fibers 45 treated by my process may be dyed with the usual materials and processes used for cotton fibers and goods.

What I claim is:—

1. A process for cleansing and softening flax, hemp, cotton and like fiber and products formed therefrom in which the materials are boiled in an alkaline solution containing a mixture of an alcohol and naphthenic acid.
2. A process for cleansing and softening flax, hemp, cotton and like fiber and products formed therefrom in which the materials are boiled in an alkaline solution containing a mixture of an alcohol and naphthenic and stearic acids.
3. A process for cleansing and softening flax, hemp, cotton and like fiber and products formed therefrom in which the materials are boiled in an alkaline solution containing a mixture of an alcohol and naphthenic acid and a fatty acid containing 18 carbon atoms.
4. A process for cleansing and softening flax, hemp, cotton and like fiber and products formed therefrom in which the materials are boiled in an alkaline solution containing a mixture of an alcohol and naphthenic acid, the solution being then removed and the materials treated with warmed alcohol and naphthenic acid.

5. A process for cleansing and softening flax, hemp, cotton and like fiber and products formed therefrom in which the materials are boiled in an alkaline solution containing a mixture of an alcohol and naphthenic acid, the solution being then removed and the materials treated with warmed alcohol and naphthenic acid.

6. A process for cleansing and softening flax, hemp, cotton and like fiber and products formed therefrom in which the materials are boiled in an alkaline solution containing a mixture of an alcohol and naphthenic acid, the solution being then removed and the materials treated with warmed alcohol and naphthenic acid.

7. A process for cleansing and softening flax, hemp, cotton and like fiber and products formed therefrom in which the materials are boiled in an alkaline solution containing a mixture of an alcohol and naphthenic acid, the solution being then removed and the materials treated with warmed alcohol and naphthenic acid.

8. A process for cleansing and softening flax, hemp, cotton and like fiber and products formed therefrom in which the materials are boiled in an alkaline solution containing a mixture of an alcohol and naphthenic acid, the solution being then removed and the materials treated with warmed alcohol and naphthenic and stearic acids.

9. A process for cleansing and softening flax, hemp, cotton and like fiber and products formed therefrom in which the materials are boiled in an alkaline solution containing a mixture of an alcohol and naphthenic acid, the solution being then removed and the materials treated with warmed alcohol and naphthenic acid and a fatty acid containing 18 carbon atoms.

10. A process for cleansing and softening flax, hemp, cotton and like fiber and products formed therefrom in which the materials are boiled in an alkaline solution containing a mixture of an alcohol and naphthenic and stearic acids, the solution being then removed and the materials treated with warmed alcohol and then washed and dried.

11. A process for cleansing and softening flax, hemp, cotton and like fiber and products formed therefrom in which the materials are boiled in an alkaline solution containing a mixture of an alcohol and naphthenic and stearic acids, the solution being then removed and the materials treated with warmed alcohol and naphthenic acid and then washed and dried.

12. A process for cleansing and softening flax, hemp, cotton and like fiber and products formed therefrom in which the materials are boiled in an alkaline solution containing a mixture of an alcohol and naphthenic and stearic acids, the solution being then removed and the materials treated with warmed alcohol and naphthenic and stearic acids and then washed and dried.

13. A process for cleansing and softening flax, hemp, cotton and like fiber and products formed therefrom in which the materials are boiled in an alkaline solution containing a mixture of an alcohol and naphthenic and stearic acids, the solution being then removed and the materials treated with

warmed alcohol and naphthenic acid and a fatty acid containing 18 carbon atoms, and then washed and dried.

12. A process for cleansing and softening flax, hemp, cotton and like fiber and products formed therefrom in which the materials are boiled in an alkaline solution containing a mixture of an alcohol and naphthenic acid and a fatty acid containing 18 carbon atoms, the solution being then removed and the materials treated with warmed alcohol and naphthenic acid and then washed and dried.

13. A process for cleansing and softening flax, hemp, cotton and like fiber and products formed therefrom in which the materials are boiled in an alkaline solution containing a mixture of an alcohol and naphthenic acid and a fatty acid containing 18 carbon atoms, the solution being then removed and the materials treated with warmed alcohol and naphthenic and stearic acids and then washed and dried.

14. A process for cleansing and softening flax, hemp, cotton and like fiber and products formed therefrom in which the materials are boiled in an alkaline solution containing a mixture of an alcohol and naphthenic acid and a fatty acid containing 18 carbon atoms, the solution being then removed and the materials treated with warmed alcohol and naphthenic acid and a fatty acid containing 18 carbon atoms and then washed and dried.

15. A process for cleansing and softening flax, hemp, cotton and like fibers and products formed therefrom in which the materials are boiled in an alkaline solution containing 1% of the weight of said materials of ethyl alcohol mixed with 5% of alcoholic impurity and $\frac{1}{2}\%$ of naphthenic acid.

16. A process for cleansing and softening flax, hemp, cotton and like fibers and products formed therefrom in which the materials are boiled in an alkaline solution containing a mixture of an alcohol, naphthenic and stearic acids and light coal oil substantially as described. 45

17. A process for cleansing and softening flax, hemp, cotton and like fibers and products formed therefrom in which the materials are boiled in an alkaline solution containing a mixture of an alcohol, naphthenic and stearic acids and light coal oil the solution being then removed and the materials treated with warmed alcohol, naphthenic and stearic acids and with light coal oil. 50 55

18. A process for cleansing and softening flax, hemp, cotton and like fibers and products formed therefrom in which the materials are boiled in an alkaline solution containing a mixture of an alcohol, naphthenic acid and a fatty acid containing 18 carbon atoms and light coal oil substantially as described. 60 65

19. A process for cleansing and softening flax, hemp, cotton and like fibers and products formed therefrom in which the materials are boiled in an alkaline solution containing a mixture of an alcohol, naphthenic acid and a fatty acid containing 18 carbon atoms and light coal oil, the solution being then removed and the materials treated with warmed alcohol, naphthenic and oleic acids and light coal oil substantially as described. 70 75

In testimony whereof I have hereunto set my hand in the presence of two subscribing witnesses.

WLADIMIR SCHEWELIN.
